MERTON L. DODGE, OF SEATTLE, WASHINGTON

DOORCHECK

Application filed January 27, 1926. Serial No. 84,035.

This invention relates to improvements in door checks and more particularly to devices of that character adapted to be fixed to a door to hold it in open position; it being the principal object of the invention to provide a device suitable for use on garage, barn or factory doors and which comprises a pivotally mounted sprag that may be moved between functional and non-functional positions by the action of foot pedals which makes it unnecessary for one to stoop, or to use the hands, in setting or releasing the sprag.

It is also an object of the invention to provide a door check as above stated which may be used satisfactorily on doors of residences or offices as a means of retaining them in open position and which will not mar or damage the floor.

Other objects reside in the details of construction whereby the sprag is actuated by a pair of foot pedals; one of which, when pressed downwardly, actuates the sprag into functional position and the other, when pressed downwardly, raises it to non-functional position and re-sets the first pedal.

In accomplishing these and other objects of the invention, I have provided the improved details of construction, the preferred forms of which are illustrated in the accompanying drawings, wherein—

Figure 1 is a perspective view showing a door check, embodied by the present invention, as attached to a door.

Figure 2 is a side elevation, showing the sprag set to hold the door against closing movement.

Figure 3 is a front view of the device.

Figure 4 is a cross section taken on line 4—4 in Figure 2.

Figure 5 is a detail of an alternative construction with the sprag equipped with a rubber knob at the end.

Figure 6 is a perspective view of an alternative construction.

Referring more in detail to the drawings—

1 designates a door such as that used on a garage, or in a residence and which would be hinged at one vertical edge to swing between open and closed positions. Attached 50 to the swinging edge of the door, on the in-

side, is a door check embodied by this invention and which may be used to retain the door in open position. The device comprises a casting 2 provided at opposite sides with laterally projecting ears 3, adapted to receive screws or bolts 4 therethrough to secure it to the door, and having two spaced apart, forwardly projecting flanges 5 and 6 between which a sprag 7 is pivotally mounted on a pivot pin 8 extended through the said flanges, 55 so that it may swing in a vertical plane perpendicular to the door.

For use on garage, barn or factory doors, the end of the sprag would preferably be pointed so that it would hold to the best advantage when engaged with a cement or wooden floor, but when the device is provided on office or residence doors, it preferably would be equipped at the end with a rubber or fibre knob, as indicated at 9 in Figure 5, 60 65 70 so as to avoid marring or damaging the floor.

The device is so placed on the door that when the sprag is in use it will project downwardly at about a thirty degree angle with the surface of the door. When not in use it rests against the door in an upwardly extended position, as indicated in dotted lines in Figure 2 with its upper end lying against the door within the vertical plane of the pivot pin so that, by its own weight, it is held in 75 80 place.

Slidably mounted in vertical guideways 10 and 11 formed respectively in the flanges 5 and 6 are plates 12 and 13 provided at their upper ends with laterally turned pedal portions 14 and 15. These plates lie in planes that are parallel with the vertical plane through which the sprag swings and each has a longitudinal slot 16 in its body portion.

Cast integral with or otherwise fixed to 90 the opposite side faces of the pivoted end of the sprag 7 are gears 17 and 18 which are disposed respectively within the slotted portions 16 of plates 12 and 13. The slot in plate 12 is provided along its forward edge with gear teeth 19 which operate in mesh with the teeth of gear 17 and along the rearward edge of the slot in plate 13 are gear teeth 20 which mesh with the teeth of gear 18. The plates are so connected with the sprag that when 95 100

the sprag is in functional position, as in Figure 1, the plate 13 is in elevated position and plate 12 is in lowered position. When the sprag is raised, the relation of the plates is reversed.

Assuming that the device is so constructed and attached to the door, and that the sprag is in non-functional position, as shown in dotted lines in Figure 2, to use the device to hold the door in open position, the plate 12 is pressed downwardly by pressure on pedal 14 which, through gear 17, swings the sprag to downwardly extended position so that its pointed end rests in holding contact with the floor. During this movement of the sprag the plate 13 is raised. Then, when it is desired to raise the sprag to release the door, the plate 13 is moved downwardly by pressure on foot pedal 15 and through gear 18 it is swung upwardly against the door where it remains due to the fact that its own weight is within the vertical plane of the pivot pin.

In Figure 6, I have illustrated an alternative construction in which the rack plate 12 and its geared connection with the spring is eliminated and the sprag is adapted to be lifted by downward pressure on the pedal portion of plate 13 and is provided near its pivotal point with an outwardly projecting arm 25 that may be pushed downwardly to cause the sprag to swing outwardly and downwardly to functional position.

Such devices may be made in various sizes, suitable for various uses and may be provided with or without the protective ball on the end of the sprag.

Having thus described my invention, what I claim as new therein and desire to secure by Letters-Patent, is:

1. A door check comprising a mounting having means for attachment to a door and comprising spaced apart flanges with vertical guideways formed therein, a pivot pin extending between the said flanges, a sprag mounted at one end on said pin to swing between functional and non-functional positions, a gear on each side of the sprag concentric with said pivot pin, plates slidable in said guideways having rack teeth in mesh with said gears; one of said plates being operable downwardly to swing the sprag upwardly and the other plate being operable downwardly to swing the sprag to downward position and each of said levers being reset by actuation of the other lever.

2. A door check comprising a mounting having means for attachment to a door and comprising spaced apart flanges with vertical guideways formed therein, a pivot pin extended between the said flanges, a sprag mounted at one end on said pin to swing between functional and non-functional positions, a gear on each side of the sprag concentric with said pivot pin, plates slidable in said guideways having vertical slots therein

for receiving said gears; the slot of one of said plates having teeth along one edge in mesh with the gear at that side of the sprag and the slot of the other plate having teeth along its opposite edge in mesh with the other gear; said plates having laterally turned pedals at their upper ends whereby the plates may be actuated downwardly to swing the sprag between functional and non-functional positions.

3. A door check comprising a mounting adapted for attachment to a door, a sprag pivotally fixed to the mounting to swing into and from holding contact with a floor and a pair of setting devices each having operative connection with the sprag and extending from the mounting, one of said devices being operable inwardly, for setting the sprag, the other being operable inwardly for releasing the sprag and each of said devices being re-set by the inward actuation of the other and through its connection with the sprag.

Signed at Seattle, King County, Washington, this 21st day of October, 1925.

MERTON L. DODGE.
